UNITED STATES PATENT OFFICE.

FRANK WALLBERG, OF JERSEY CITY, NEW JERSEY, ASSIGNOR OF ONE-HALF OF THE INVENTION
LAWRENCE, OF BROOKLYN, NEW YORK.

FLYING-MACHINE.

1,123,438.

Specification of Letters Patent.

Patented Jan. 5, 1915.

Application filed February 15, 1911. Serial No. 308,515.

To all whom it may concern:

Be it known that I, FRANK WALLBERG, citizen of the United States, residing at Jersey City, in the county of Hudson and State of New Jersey, have invented certain new and useful Improvements in Flying-Machines, of which the following is a specification.

This invention relates to improvements in flying machines and has for its object to provide a machine having its planes so fully under the control of its operator that practically all danger of accident through tipping of the machine is eliminated.

Another and the main object of the invention is to provide an aeroplane so constructed that its forward plane may be shifted transversely of its framework and in perfect unison with its rudder so that perfect stability is assured at all times.

With the above and other objects in view, I have invented the aeroplane illustrated in the accompanying drawings, in which,

Figure 1 is a bottom plan view of my improved aeroplane, Fig. 2 is a side elevation thereof, Fig. 3 is an enlarged detail perspective view of a forward or stability plane, partially broken away, Fig. 4 is a front elevation of the device, and Fig. 5 is an enlarged perspective view of the rear plane and means for shifting same.

Referring to the accompanying drawings, 1 is a framework constructed of horizontal bars 2, 3, 4, 5, 6, 7, and 8, the latter two bars 35 having upwardly curved forward ends 9 and 10; and the vertical rods 11, 12, 13, and 14. The frame work is braced by stay rods 15, 16 and 17.

The horizontal rods 2, are provided with 40 bearings 18 on their forward ends for the curved sliding support 19 of the forward plane 20, and the vertically disposed rods 14 are provided with bearings for pivotally supporting a horizontal rod 21 to which is 45 fixed a pair of curved arms 22, the forward ends of which are provided with bearings 23 in which the curved sliding support 24 of the forward plane 20 operates. The curved supports 19 and 24 being slidable in 50 the bearings 18 and 23 permit of a transverse movement of the plane 20 on said framework and this movement is obtained in the following manner: The plane 20 is provided with a pair of curved supports 55 25 and 26 transverse of said plane to which

are fixed the ends of the supports 19 and 24. Guy ropes 27 and 28 have one of their ends secured to said supports 25 and 26 at 29 and 30, and the other end loosely secured to the end 31 of the steering rod 32, 60 which is supported upon a pivoted bearing member 33 which permits of lateral movement of the steering rod by means of which the plane 20 may be shifted transversely of said frame, as previously stated, and as indicated in dotted lines in Fig. 1 of the drawings. The member 33 is pivotally mounted upon oppositely disposed members 34 which are held by the rods 3. The steering rod 32 is rotatably mounted in an opening or bearing (not shown) in the bearing member 33 and has a steering wheel 35 on the free end thereof. One end of the rope 36 is secured to the movable rod 38 which is moved up and down by the rope 36, and 75 which is fixed to the arms 22 and passes over a fixed rod 37 and is wrapped a number of times around the drum 38^a on the steering rod 32 in order to receive sufficient frictional engagement therewith. The other end of said rope is also secured to the movable rod 38, it will then be seen that by rotating the wheel 35 in one direction or the other, the rope 36 will be caused to move vertically and will consequently raise and 80 lower the rod 38 by the vertical movement of the rope, which in turn operates the pivoted lever arms 22, which are fixed to the support 24 of the plane 20, enabling the operator to regulate the angle of incidence 85 thereof. The curved arms 22 are pivotally mounted on the transverse rod 21 and are connected at their inner ends by a rod 38^b which is vertically movable by means of the cord 36. The outer ends of the rods 22 90 have loosely mounted in bearings 23 thereon the sliding support 24 which is fixed at either end to the curved plane supports 26. As the other plane support 19 is pivotally mounted on the frame work of the machine 95 it will readily be seen that the angle of incidence of the plane 20 may be readily changed by rotation of the steering rod 32.

To the rear of the framework a plane 39 is secured by the vertical rods 11 and 12. 100 To the vertical rods 11 is fixed a horizontal rod 40 provided with a bearing 40 upon which is pivotally mounted a vertical upright rod 41, the upper end of which is held in a bearing plate 42, which is held in po- 110

sition by the cables 42^a and 43, the lower ends of which are secured to the frame of the plane 39. To the rod 41 is secured a frame 44 in which the steering rudder 45 is pivotally mounted upon a vertical centrally disposed pivot rod 46, the lower end of which has a fixed pulley wheel 47. To the rod 48 of the frame 44 is secured a cable 49, the portion 50 of which diverges to one side of the frame of the machine and the other portion 51 of which diverges to the other side of the frame, these cables run parallel with the frame to eyelets 52 and 53 and there turn in at right angles and the ends are secured to the post 54 on the frame of the forward plane 20, thus when the forward plane is shifted to the right, the frame 44 is automatically shifted to the left and vice versa. A cable 55 is passed once around the pulley 47 and has its opposing ends fixed to each of the rods 11, the first being drawn very taut, so that when the frame 44 is shifted, the cable operating on the pulley will revolve same and shift the angle of the rudder 45 to an angle opposing that of the frame 44, except when said frame is in a position parallel with the line of the machine at which time the rudder will be in a line with the frame 44, this operation being shown in the full and dotted lines in Fig. 1.

It will be seen that to shift the rudder to guide the machine to either the right or to the left it will be necessary to shift the forward plane in the direction in which it is desired to turn and at the same time raise the end of said plane at the end toward which the machine is turning, and lower the opposite end thereof thus giving a greater bearing surface toward the direction in which the machine is turning, and preventing the possibility of the machine tipping and assuring perfect stability. A platform is constructed of slats 55^a or other material to support the operator's seat, and an engine (not shown) by which the device is propelled. The plane 20 has its corners 56 slightly turned upward so that in descending there will be less resistance to the downward movement. The steering bar 32 controls the entire operation of the machine. By shifting to the right or left the longitudinal movement is controlled, and by revolving it through the medium of the wheel, the vertical movement is controlled.

In Fig. 5 a modification is shown, by means of which the position of the plane may be changed on the frame work according to the load to be carried. The uprights 57, 58, 59 and 60 which support the plane are slidably mounted upon the bars 61 and 62, the uprights 57 and 60 are connected by a rod 63, and the uprights 58 and 59 are connected to a rod 64. Centrally connected to the rods 63 and 64 is a rack 65

which is operated by a gear 66 on the lever arm 67, by means of which the said movement of the plane is obtained.

The construction of the rudder as above described is such that the movement thereof toward the right or left will tend to raise the side of the machine in the direction in which the machine is being turned, this providing a most efficient stability device in itself.

I claim and desire to secure by Letters Patent:—

1. A flying machine comprising a frame, a plane mounted thereon, means for transverse movement of said plane, means for changing the longitudinal angle of said plane, means for changing the transverse angle of said plane, a rudder mounted on said frame, means for simultaneous movement of said rudder with transverse movement of said plane.

2. A flying machine comprising a frame, a plane mounted thereon, means for transverse movement of said plane, means for changing the longitudinal angle of said plane, means for changing the transverse angle of said plane, a rudder mounted on said frame, and means on said plane for operating said rudder.

3. A flying machine comprising a frame, a plane mounted thereon, means for transverse movement of said plane, means for changing the longitudinal angle of said plane, means for changing the transverse angle of said plane, a rudder mounted on said frame, means on said plane for operating said rudder, said plane supported upon longitudinal bars.

4. A flying machine comprising a frame, a plane mounted thereon, means for transverse movement of said plane, means for changing the longitudinal angle of said plane, means for changing the transverse angle of said plane, a rudder mounted on said frame, means on said plane for operating said rudder, said plane supported on longitudinal bars, said bars being longitudinally curved.

5. A flying machine comprising a frame, a plane mounted thereon, means for transverse movement of said plane, means for changing the longitudinal angle of said plane, means for changing the transverse angle of said plane, a rudder mounted on said frame, means on said plane for operating said rudder, said plane supported on longitudinal bars, said bars being longitudinally curved, one of said bars being pivotally mounted on said frame.

6. A flying machine comprising a frame, a plane mounted thereon, means for transverse movement of said plane, means for changing the longitudinal angle of said plane, means for changing the transverse angle of said plane, a rudder mounted on

5 said frame, means on said plane for operating said rudder, said plane supported on longitudinal bars, said bars being longitudinally curved, one of said bars being pivotally mounted on said frame, the other of said bars being mounted upon lever arms.

7. A flying machine comprising a frame, a plane and a steering device, said steering device consisting of a pivotally mounted 10 vertical frame having a vertically mounted plane thereon, said vertical plane being mounted at its transverse central portion and means for giving a horizontal movement to said vertical frame, said movement 15 of said frame adapted to cause a horizontal movement of said plane and means for operating the movement of said planes simultaneously, said means connecting said planes.

8. A flying machine comprising a frame, 20 a plane slidably mounted transversely thereof, means for changing the angle of incidence of said plane, said means consisting of slidable arcuate supports, and additional arcuate supporting members transverse of said first supports upon which said first supports are mounted.

9. A flying machine comprising a frame, a plane slidably mounted transversely thereof, means for changing the angle of incidence of said plane, said means consisting of slidable arcuate supports, additional arcuate supporting members transverse of said first supports upon which said first supports are mounted, whereby said plane 35 may be tilted in the direction of the travel of said machine.

10. An aeroplane consisting of a frame, a plane having transverse movement thereon, a rudder, the transverse movement of said 40 plane adapted to operate said rudder, slid- able supports upon which said plane is mounted, said supports being arcuate whereby the movement thereof will tilt said plane, a pair of members upon which said 45 supports are mounted, said members being arcuate, a horizontally movable steering device having connection with said members, the horizontal movement of which moves said plane transversely of said frame.

50 11. An aeroplane consisting of a frame, a plane having transverse movement thereon, a rudder, the transverse movement of said plane adapted to operate said rudder, slid- able supports upon which said plane is 55 mounted, said supports being arcuate whereby the movement thereof will tilt said plane, a pair of members upon which said supports are mounted, said members being arcuate, a horizontally movable steering de- 60 vice having connection with said members, the horizontal movement of which moves said plane transversely of said frame, said device being revoluble whereby the angle of incidence of said plane is obtained.

65 12. An aeroplane consisting of a frame

having a plane thereon bodily movable transversely thereof, the movement of said plane adapted to change the transverse angle thereof, means for forwardly and rearwardly tilting said plane, a rudder on said 70 aeroplane, the transverse movement of said plane adapted to actuate the movement of said rudder.

13. An aeroplane consisting of a frame having a plane thereon bodily movable 75 transversely thereof, the movement of said plane adapted to change the transverse angle thereof, means for forwardly and rearwardly tilting said plane, a rudder on said aeroplane, the transverse movement of 80 said plane adapted to actuate the movement of said rudder and an additional plane on said aeroplane adapted to be moved longitudinally thereon whereby said aeroplane may be properly balanced.

85 14. An aeroplane consisting of a frame, a plane having transverse movement thereon, and a rudder, the transverse movement of said plane adapted to operate said rudder.

90 15. An aeroplane consisting of a frame, a plane having transverse movement thereon, and a rudder, the transverse movement of said plane adapted to operate said rudder, 95 slidable supports upon which said plane is mounted.

16. An aeroplane consisting of a frame, a plane having transverse movement thereon, and a rudder, the transverse movement of said plane adapted to operate said rudder, 100 slidable supports upon which said plane is mounted, said supports being arcuate whereby the movement thereof will tilt said plane.

105 17. An aeroplane consisting of a frame, a plane having transverse movement thereon, and a rudder, the transverse movement of said plane adapted to operate said rudder, 110 slidable supports upon which said plane is mounted, said supports being arcuate whereby the movement thereof will tilt said plane, a pair of members upon which one of said supports is mounted.

115 18. An aeroplane consisting of a frame, a plane having transverse movement thereon, and a rudder, the transverse movement of said plane adapted to operate said rudder, 120 slid- able supports upon which said plane is mounted, said supports being arcuate whereby the movement thereof will tilt said plane, a pair of members upon which said supports are mounted, said members being arcuate.

125 19. An aeroplane consisting of a frame, a plane having transverse movement thereon, a rudder, the transverse movement of said plane adapted to operate said rudder, slid- able supports upon which said plane is mounted, said supports being arcuate whereby the movement thereof will tilt said 36

- plane, a pair of members upon which said supports are mounted, said members being arcuate, a horizontally movable steering device having connection with said members, 5 the horizontal movement of which moves said plane transversely of said frame, said device being revoluble whereby the angle of incidence of said plane is obtained, flexible means connecting said device and said members.
20. An aeroplane consisting of a frame, a plane, slidable arcuate arms upon which said plane is mounted, one of said arms being pivotally mounted on said frame.
- 15 21. An aeroplane consisting of a frame, a plane, slidable arcuate arms upon which said plane is mounted, one of said arms being pivotally mounted on said frame, arcuate arms transverse of said first arms upon which said first arms are mounted.
- 20 22. An aeroplane consisting of a frame, a plane bodily movable across said frame and means whereby said plane is tilted as it is moved and a rudder actuated by said plane.
- 25 23. An aeroplane consisting of a frame, a plane bodily movable across said frame and means whereby said plane is tilted as it is moved and a rudder actuated by said plane, said means consisting of arcuate supports for said plane.
24. An aeroplane consisting of a frame, a plane bodily movable across said frame and means whereby said plane is tilted as it is moved and a rudder actuated by said plane, said means consisting of arcuate supports for said plane, and means for changing the angle of incidence of said plane.
- 25 25. An aeroplane consisting of a frame, a plane bodily movable across said frame, means whereby said plane is tilted as it is moved and a rudder actuated by said plane, said means consisting of arcuate supports
- for said plane, and means for changing the angle of incidence of said plane, said means 45 consisting of arcuate members partially supporting said plane.
26. An aeroplane consisting of a frame, a plane, slidable arcuate arms upon which said plane is mounted, one of said arms 50 being pivotally mounted on said frame, arcuate arms transverse of said first arms upon which said first arms are mounted, and means for raising and lowering one of said first arms.
27. In a device of the kind described, a body member, a cradle carried by said body member, bearings carried by said cradle, a curved supporting rod slidable in said bearings, and a plane secured to the ends of said 60 rod.
28. In a device of the kind described, a body member, a cradle, bearings carried by said cradle, a curved rod slidable with respect to said cradle and in said bearings, 65 means for controlling the sliding movement of said supporting rod, and a plane attached to the ends of said rod.
29. In a device of the kind described, a body member, a cradle, a supporting rod, a 70 curved brace-rod extending transversely of said supporting rod and slidable with respect to said cradle, and a plane secured to the ends of said supporting rod.
30. In a device of the kind described, a 75 body member, a cradle having apertured bosses, a curved supporting member slidable in said bosses, and a plane connected to said supporting member.
- In testimony whereof I affix my signature 80 in presence of two witnesses.

FRANK WALLBERG.
